[57] CLAIM

The ornamental design for an electronic copier, as shown and described.

DESCRIPTION

FIG. 1 is a front elevational view of an electronic copier showing my new design;

FIG. 2 is a top plan view thereof;

FIG. 3 is a right side elevational view thereof;

FIG. 4 is a left side elevational view thereof;

FIG. 5 is a rear elevational view thereof;

FIG. 6 is a bottom plan view thereof;

FIG. 7 is a perspective view thereof; and

FIG. 8 is a perspective view of the electronic copier of FIG. 1 in operation with a cover on a noncopied manuscript-setting section kept raised.

FIG. 1

FIG. 2
